UNITED STATES PATENT OFFICE.

JOHN MACGREGOR, OF BOSTON, MASSACHUSETTS, ASSIGNOR, BY MESNE ASSIGNMENTS, TO MACGREGOR INSTRUMENT COMPANY, OF BOSTON, MASSACHUSETTS, A CORPORATION OF MASSACHUSETTS.

SYRINGE.

1,277,445.

Specification of Letters Patent.

Patented Sept. 3, 1918.

Application filed March 13, 1914. Serial No. 824,523.

To all whom it may concern:

Be it known that I, JOHN MACGREGOR, a citizen of the United States, and a resident of Boston, county of Suffolk, and State of 5 Massachusetts, have invented an Improvement in Syringes, of which the following description, in connection with the accompanying drawings, is a specification, like characters on the drawings representing like 10 parts.

This invention relates to syringes and pertains more particularly to that type of dental syringe used, for example, for injecting anesthetics under heavy pressure.

15 Among other objects, the invention is intended to provide what may be called a high pressure syringe preferably arranged to be filled by aspiration and constructed in such a manner and of such materials as to be 20 readily sterilized by boiling, without causing any deterioration in the parts or operation of the syringe. Other features of the invention provide for measuring and determining accurately the voluminal contents of 25 the syringe, and for the convenient and efficient operation thereof.

The character of the invention may be readily understood by reference to one illustrative embodiment shown in the accompanying 30 drawings, in which:

Figure 1 is a side elevation partly in section, of the illustrative syringe;

Fig. 2 is a detached detail, a part of the piston stem being shown in section to illustrate a preferred adjustable connection between said stem and the handle;

Fig. 3 is a top view of a preferred form of handle;

Fig. 4 is a transverse section on the line 40 4—4 of Fig. 1; and

Fig. 5 is an enlarged detail showing a preferred form of needle point, to the use of which certain features of the illustrative syringe are particularly adapted.

45 Fig. 6 is a perspective showing the relative positions of the hand of an operator and the illustrative type of handle shown in Fig. 1.

Referring to the drawings, the illustrative syringe comprises a barrel 6 containing 50 a piston 7 which closely fits the interior of the barrel, although in sliding contact therewith.

At the lower end of the barrel is provided 55 a conical seat 8 communicating with an out-

let 9 through which the contents of the barrel are ejected, this outlet preferably passing through a tip 10 threaded to receive a hub 11 which carries the cannula 12 of the

60

An annular recess 13 is provided in the lower end of the barrel 6, encircling the tip 10; countersunk in said recess 13 is a metallic packing which may be provided conveniently by a tin washer permanently 65 fitted into the recess. When the hub 11 of the needle is secured upon the tip 10 it may be tightened against the metallic packing in the recess 13 so as to form a hermetic closure between the outlet 9 and the needle.

70

The concave conical surface of the seat 8 preferably directly intersects the interior cylindrical surface of the barrel 6; in other words, the cylindrical interior surface of the barrel merges directly into the converging conical surface of the seat 8 without any intervening shelf-like surface upon which a minute quantity of the contents of the syringe might lodge and fail of being ejected.

80

The lower end 14 of the piston 7 is ground in conical shape to fit precisely upon the seat 8; and the concave conical end of the piston directly intersects the cylindrical exterior surface of the piston. Thus the piston as a whole, when in the closed position shown in Fig. 1, fits very accurately the interior of the barrel 6 and the seat 8 so that upon the final closing movement of the piston the entire contents of the barrel are completely and effectually expelled, and the outlet 9 is to all intents and purposes hermetically closed in readiness for introducing another charge to the barrel by aspiration.

85

When a new charge is to be drawn into the barrel of the syringe, the point of the needle may be inserted in the liquid to be used, and the piston drawn gradually outwardly from the position shown in Fig. 1. The first effect of this withdrawal of the piston 100 is to open minutely the needle valve provided by the lower conical end of the piston in coöperation with the conical seat 8, thereby drawing in gradually at the outset the liquid charge. With further withdrawal of 105 the piston the needle valve is opened more widely but still gradually, until the inflow of the liquid is well under way. This minute opening of the needle valve at the outset of the aspirating movement is of impor-

90

100

105

110

tance in that it permits the inflow of the liquid to start more or less gradually so as to minimize, and in fact practically eliminate, the tendency for air to be drawn from 5 the upper part of the barrel past the piston into the lower liquid containing end of the barrel. As is well understood in the art, the presence of air in the barrel chamber with the liquid is absolutely necessary to be 10 avoided. When the needle is inserted in the liquid there is, of course, some infinitesimal volume of air in the bore of the needle and the outlet 9, but this is so small as to be negligible, and the principal consideration is to avoid any inflow of air around the 15 piston. This purpose is effectually served by the arrangement described.

The arrangement just described, which in and of itself avoids any substantial tendency to draw in air around the cylinder 7, obviates the necessity for a packing around the piston stem 15 and therefore the cap 16, which is preferably employed to close the upper end of the barrel 6 and to give the 20 instrument a finished appearance, may encircle the piston stem only loosely.

It has been customary in certain types of 25 syringe heretofore used, to provide a packing, such as by leather washers or the like, around the piston stem. Any such packing, however, is subject to practically complete 30 deterioration in a very short time when the parts of the instrument are sterilized by boiling; the heat in boiling promptly destroys the effectiveness of the packing.

It will be observed that the described instrument contains no packing which is in any degree subject to deterioration from 35 boiling. In fact, the only thing employed 40 in the nature of a packing is the preferably metallic washer 13, countersunk in the lower end of the barrel, but this is obviously thoroughly durable and unharmed by boiling.

To meet the practical necessity for boiling 45 in order to sterilize the instruments of the type described, the barrel, its seat 8, and the tip 10, are preferably integral with each other, being formed of a single cylinder; and to suit the heavy pressure intended to 50 be exerted upon the contents in injecting them for purposes of dental anesthesia, the walls of the cylinder 6 are of substantial thickness. The integral character of the barrel 6, seat 8 and tip 10 also contributes 55 obviously to the strength of the instrument appropriate to a high pressure syringe.

The piston stem 15 is preferably graduated 60 to show in its different positions the interior volume of the chamber of the barrel 60 below the piston. The upper edge of the cap 16 may serve conveniently as the index co-operating with these graduations. When 65 in the position shown in Fig. 1, the zero graduation of the stem is opposite the top edge of the cap 16. There is an important

relation between these graduations and the needle valve construction comprising the piston end 14 and its seat 8. The fact that the interior cylindrical surface of the barrel merges directly with the conical concave surface of the seat 8, thereby avoiding any lodgment of the contents and providing for the complete ejection thereof—and also the functioning of this organization to avoid an inflow of air around the piston,—renders 70 it certain that the inflow of liquid upon withdrawal of the piston will always accurately fill the chamber of the barrel below the piston and will occupy completely the volume indicated by the graduations on the 75 piston stem.

For relatively operating the barrel 6 and piston 7, handles 17 and 18 are provided. The handle 17 is preferably rotatably mounted on the barrel 6 between brazed or 80 otherwise fixed collars 17^a and 17^b.

The handle 18 (see Fig. 2) has preferably a shank 20 provided with a double pitch thread screwing into the upper end of the piston stem 15. This arrangement permits 90 the handle 18 to be adjusted lengthwise of the piston stem to suit hands of different dimensions and also permits the handle 18 to be adjusted farther away from the handle 17, to permit a better purchase by the operator in the final stroke of the piston when 95 it is desired to complete an injection under heavy pressure.

Preferably the piston 7 is freely rotatable about its own axis in the barrel 6, so that 100 with or without the adjustment provided by the shank 20, both the handle 17 (being rotatably mounted on the barrel 6) and the handle 18 are freely rotatable in relation to the needle 12. A preferred form of needle 105 is shown in enlarged detail in Fig. 5, it consisting of a minute tube ground obliquely and unsymmetrically to provide a large opening in combination with a sharp point and sharp edges surrounding the opening. Obviously, when such an unsymmetrical needle is inserted subcutaneously, any twisting of the needle about its longitudinal axis might cause a substantial cutting of the tissues which would be highly undesirable. 110 Similarly, if a curved needle of any sort were employed any twisting thereof would be highly undesirable. Any tendency to twist the needle is minimized by the arrangement described by which either or both of 115 the handles 17 and 18 may be freely rotated in relation to the needle; and this arrangement also admits of the operator's shifting his hand to any comfortable or convenient position without necessarily twisting the 120 needle or changing its position in any degree.

The described instrument is intended to be held by placing the first and second fingers beneath the two ends of the handle 17 130

and astraddle of the barrel 6, the palm of the hand resting upon the top of the handle 18. The illustrative form of handle shown in Figs. 1 and 3 is especially desirable.

5 A rounded portion 22 is arranged to be positioned substantially on the median line lengthwise the palm of the hand and about two-thirds of the distance from the knuckles to the wrist. A pommel 23 is arranged to 10 engage the crotch between the thumb and the forefinger. In plan view as shown in Fig. 3 the pommel 23 is arranged on a line oblique to the length of the handle 22 so that the pommel may stand in substantially 15 the plane of the outer side of the crooked forefinger while the remainder of the handle extends across the palm in a direction substantially parallel to the length of the extended thumb. Preferably a depression 24 20 of considerable depth is provided adjacent the pommel 23 to receive the flesh between the thumb and the knuckle of the forefinger and permit the pommel 23 to engage that portion of the hand firmly to prevent any 25 slipping of the handle 18 relative to the hand, in operation. The adjacent portions of the thumb entering the recess 24 and bearing upon both sides of that recess effectually prevent any slipping of the handle 30 18 in either direction along its length and the pommel 23 being gripped between the thumb and knuckle of the forefinger, is thereby prevented from any transverse slipping. All such features as these are 35 of particular importance in a high pressure syringe whereby anesthetics or the like are intended to be injected under heavy pressure, and necessarily with the greatest precautions against slippage.

40 It is to be understood that the particular embodiment of the invention described above and shown in the drawings, is disclosed merely for purposes of illustration and the invention is not limited to the particular construction, organization and mode 45 of operation thereof. On the contrary, the invention may be variously embodied, and, while it is desirable that all the features of the invention be used conjointly for the 50 greatest advantage, certain of the features

may be used separately, or in sub-combinations.

Claims:

1. A syringe of the character described comprising, in combination, a barrel, a piston in the barrel; a non-symmetrical needle secured to the outlet end of said barrel; and handles upon the barrel and piston respectively and mounted to be freely rotatable 55 relatively to said needle.

60 2. A syringe of the character described comprising, in combination, a barrel; a piston; means for attachment of a needle at the outlet end of the barrel; and handles on the barrel and piston respectively freely 65 rotatable in relation to said means for attachment of the needle.

65 3. A syringe of the character described comprising, in combination, a barrel; a piston; a handle on the barrel adapted to be 70 engaged by the operator's fingers; and a handle on the piston adapted to rest upon the palm of the operator's hand, and having a pommel disposed obliquely in relation to the length of the handle and bent to engage 75 the crotch between the thumb and the forefinger, and provided with a recess of substantial depth between said pommel and the axial line of the piston to receive the flesh of the hand between the thumb and 80 forefinger to prevent slipping of the handle.

80 4. A syringe of the character described comprising, in combination, a barrel; a piston; a handle on the barrel to be engaged by the operator's fingers; and a handle on 85 the piston adapted to rest upon the palm of the operator's hand, the surface of the handle to contact with the palm of the hand having a compound curve to fit the conformation of the hand from a point in the 90 crotch between the thumb and forefinger and a point in substantially the median line of the hand at the base of the thumb.

90 In testimony whereof I have signed my name to this specification, in the presence 95 of two subscribing witnesses.
